1 Claim

ABSTRACT OF THE DISCLOSURE

Substrate-containing test container for the cultivation and inspection of micro-organisms comprising a coating of said substrate on the inner surface of the side walls of said container and an insert means for supporting said coating.

BACKGROUND OF THE INVENTION

This invention relates to a substrate-containing test container and particularly a tubular container for the cultivation and inspection of micro-organisms e.g. bacteria or living cells.

It is well known to cultivate micro-organisms in flat circular dishes e.g. Petri dishes, on a substrate such as agar. Such substrate-containing Petri dishes present large surfaces available for cultivation and therefore the micro-organisms growing on a substrate in such Petri dishes can be easily inspected. Therefore, such dishes have found widespread use in clinics, hospitals etc., in which they are used for determining by cultivation the amount and type of bacteria contained in biological fluids. The bacteria cultivated in such Petri dishes are normally studied and counted by means of a microscope.

However, such substrate-containing Petri dishes are difficult to pack in such a manner that they can be sent from one place to another for example by normal post without the risk of breaking such containers during transportation.

It has been attempted to use substrate-containing glass tubes which can be packed in a more satisfactory manner. However, the surface area available for the cultivation of micro-organisms is very small in such glass tubes compared to that of Petri dishes. In order to increase the free surface area of the substrate it has been proposed to use tubes in which the portion of the glass tube which forms the basis of the substrate layer is flat and is disposed at an acute angle to the longitudinal axis of the tube.

However, such tubes can be manufactured only by using special molds and consequently, they are more expensive than normal glass tubes.

SUMMARY OF THE INVENTION

The object of the invention is to provide a simple and inexpensive substrate-containing container presenting a large free surface available for the cultivation of micro-organisms.

According to the invention there is provided a substrate-containing container having the inner surface of the side walls coated with a substrate layer.

In a preferred embodiment of the substrate container of the invention both the bottom and the side walls are coated with said substrate layer.

The substrate layer may be applied to the inner surface of the container side walls in several ways. One of the most simple ways consists in introducing a liquid substrate into the container and rotating the container about its longitudinal axis. When the fluid substrate has been uniformly distributed over the inner surface, the container is cooled to solidify the substrate.

2

The application of the substrate layer can also be effected by introducing a liquid substrate in the container and by moving said container in such a path that the fluid substrate is distributed in an even layer on the inner surfaces. The container is then cooled to solidify the substrate.

The substrate layer may also be applied by molding by means of a core which is inserted in the container and is removed after the solidification of the substrate.

Furthermore, the substrate layer may be applied by spraying a warm fluid substrate onto the inner surfaces of the container so as to build up a uniform layer on said surfaces. The substrate applied may be solidified by directing a cooling medium for example a stream of cold air onto the exterior side of the container.

A further method of applying the substrate on the inner surface of a tube consists in extruding said layer directly onto said surface.

In some cases and especially when using tubes prepared from plastic materials the adherence between the tube walls and the substrate layer is insufficient to prevent the substrate layer from being released from the side walls and fall down onto the bottom of the tube. Furthermore, since some micro-organisms liquefy the substrate during their growth it has been found difficult to maintain a uniform substrate layer on the side walls during the cultivation.

It has been attempted to eliminate these problems by using tubes having small protrusions or ribs on the inner surface of the side walls. However, the manufacture of tubes having such protrusions or ribs which serve to improve the bond between the substrate layer and the tube walls has presented serious problems when the tubes are produced by injection moulding. Thus, it is difficult to remove the mold parts forming said protrusions or ribs from the tubes. Therefore, it has been necessary to manufacture the tubes in two parts and subsequently to weld these two parts together.

Now it has been found that this complicated production of the tubes can be avoided by using a perforated insert means to be inserted in said tubes so as to support the substrate layer applied on the inner surface of the side walls.

This insert means may comprise a number of longitudinal ribs which are connected by spaced transverse ribs so as to form rectangular openings. These ribs are preferably located in such a manner that narrow openings are formed between the side walls and the exterior sides of said ribs. Thus, when applying a substrate onto the inner surface of the tube the liquid substrate flows into said openings and consequently the substrate layer will be firmly anchored to the insert means, when the liquid substrate has been solidified.

In order to facilitate the counting of the micro-organisms grown on the substrate the area of said openings is for Example 1 cm.².

The insert means can be manufactured in one step and consequently no welding operations are required. After the production of the tubes and the insert means the latter are inserted in the tubes and a substrate layer is applied onto the inner surface of the side walls of the tube.

The substrate-containing tube is preferably provided with a screw cap having on its interior side an absorbing pad. This absorbing pad serves to absorb residual liquid present in the substrate-containing tube when a liquid sample, for example urine, has been brought into contact with the substrate and subsequently has been removed from the tube.

In order to prevent the absorbing pad from being contacted by the liquid substrate when distributing said substrate in a uniform layer onto the inner surface of the side walls, the insert means preferably comprises an inwardly

extending collar provided at its upper end. The exterior side of this collar may be firmly attached to the test tube. In order to obtain an exact mounting of the insert means within the tube the insert means preferably also comprises a bottom plate having a diameter which is equal to that of the tube.

BRIEF DESCRIPTION OF THE DRAWINGS

FIG. 1 shows a longitudinal sectional view of an embodiment of a substrate-containing container according to the invention,

FIG. 2 shows a side view of a transparent substrate-containing tube accordance to the invention,

FIG. 3 shows an enlarged cross sectional view of the substrate-containing tube shown in FIG. 1, and

FIG. 4 shows an enlarged view of an insert means according to the invention.

DESCRIPTION OF THE PREFERRED EMBODIMENTS

In FIG. 1 a substrate tube 1, e.g. made from glass or a plastic material, comprises a substrate layer 2 applied onto the inner surfaces of the side walls and the bottom of said tube.

The substrate tube shown in FIGS. 2 and 3 comprises a plastic tube 3, having a screw cap 4. An insert means 5, shown in detail in FIG. 4 as comprising a bottom plate 6, vertical ribs 7, transverse ribs 8 and a collar 9, is mounted within said tube 3.

The crossing ribs 7 and 8 form openings 10 which at the lower end of the substrate tube are almost quadratic and have an area of 1 cm.². The ribs 7 and 8 do not contact the inner surface of the side walls and consequently

the liquid substrate medium which is introduced into the tube is permitted to flow in the longitudinal direction as well as transverse thereto so as to form upon cooling a uniform substrate layer 11 firmly anchored to said ribs.

The exact position of the insert means 5 within the tube 3 is controlled by the bottom plate 6 and an annular flange 12.

I claim:

1. A test tube for the cultivation and investigation of micro-organisms having a film of a solid substrate on the inner surface of the tube, and an insert means within the tube and supporting the substrate film, said insert means comprising ribs extending longitudinally of the tube and ribs extending transversely thereto and connecting said longitudinally extending ribs, said ribs being disposed inwardly of the inner surface of the tube so as to form narrow spaces between the outer side of the ribs and the inner surface of the tube, said insert means further comprising a bottom plate and an annular flange, said plate and flange extending slightly outwardly of said ribs thereby serving to center said insert means in the tube.
